UNITED STATES PATENT OFFICE.

STANLEY W. HAYES, OF RICHMOND, INDIANA, ASSIGNOR TO HAYES TRACK APPLIANCE COMPANY, OF RICHMOND, INDIANA, A CORPORATION OF INDIANA.

BUMPER POST.

Application filed October 28, 1925. Serial No. 65,323.

The invention relates to that type of bumper post in which the bumper head is supported by compression members which extend outward, downward and backward from the bumper head to bearings on the roadbed, and by tension members which extend downward, outward and usually forward from the bumper head to points in advance thereof, where they are secured to the roadbed. In 10 bumpers of this character the shock of impact is taken partly by the compression members as a downward thrust, and partly by the tension members which resist the upward pull resulting from the impact. The length 15 of the base in bumpers of this sort varies considerably, the angles of the compression members and of the tension members to the track plane being subject to alteration within a considerable range.

20 The object of the present invention includes the distribution of the compression and tension stresses, to a number of different ties, so as to provide adequate anchoring structure substantially in the track plane or 25 above it, thus avoiding special sub-structures built into the roadbed, and it also includes the organization and design of the several parts so that they can be produced by simple and inexpensive operations and quickly assembled on and connected to the roadbed. The invention further includes the special 30 means of attaching, the tension members, and also other features, which will appear below and which will be seen to be capable 35 of use in other styles of bumper posts and in other bumper structures.

Referring to the drawings: Fig. 1 is a perspective of the bumper post installed in a track section.

40 Fig. 2 is a plan of the bumper post.

Fig. 3 is a side elevation of the bumper head.

45 Fig. 4 is a front elevation of the bumper head and adjacent parts of the compression and tension members.

Fig. 5 is a plan of the bumper head.

Fig. 6 is a side elevation, partly in section, 50 of the left hand tension track fixture showing the corresponding tension member applied thereto.

Fig. 7 is an end elevation with parts broken away showing the left hand tension track fixture, and the manner in which the end of the tension member is related to it. A phan-

tom showing of a part of the tension member has been adopted for clearness.

Fig. 8 is a section on the diagonal plane indicated by section line VIII—VIII, Fig. 6.

Fig. 9 is a perspective of a tension member.

Fig. 10 is a plan of the left hand tension 60 track fixture.

Fig. 11 is a detail plan illustrating the preferred cross tie connection for the compression track fixtures, and

Fig. 12 is a side elevation of the right hand 65 compression track fixture.

In the particular embodiment of the invention illustrated in the drawings the bumper head 1 is provided at each side with downwardly, outwardly and rearwardly extending portions 2, (Fig. 3) which in the present instance are shaped to fit channel irons consisting the compression members

3. The opposite ends of the compression members abut against the shoulders 4 on the bumper head and on similar lugs or shoulders 4^a on the compression track fixtures 5 which latter are located opposite each other in the track at the inside of the rails. Each of these fixtures 5 seats on two adjacent ties, 70

spanning the space between them and also seats on the base of the rail, being spiked to the ties and secured by bolts 6 to the web of the rail against which it also seats. Compression strains are thus delivered to the ties and 75

roadbed direct instead of to the rails alone in the first instance. Movement of the compression track fixtures endwise of the rail is further resisted by the shoulders 7, placed 80

to abut against the front faces of the supporting ties. The compression fixtures are 85 connected by a cross tie-rod 8 which is preferably constructed as indicated in Fig. 11 with an upset head 9 at each end, the intermediate portion being adapted for insertion

90 laterally into corresponding aligned slots 10 in the compression fixtures before these are separated their full assembled distance, and the heads 9 being adapted to be received respectively in undercut recesses 9' (Figs. 1 and 100

11) at the outer end of each slot 10 when the fixtures are moved apart to the full assembled distance required for placing them on the rails. This method of connection avoids the

use of screw threads and constitutes a secure 105 connection. The compression fixtures 5 are further secured against displacement by longitudinal anchor bars 11 each provided at its

rear end with a down-turned hook or knuckle 12 hooked into a recess 13 on the track fixture, as indicated in Fig. 12. These bars are spiked to one or several of the ties forward 5 of the compression fixtures. The anchor bar hooks may be upturned if desired as shown for the tension track fixtures in Fig. 6. In both of the arrangements illustrated they grasp an edge extending transversely of the 10 track.

In the illustrated bumper post the bumper head 1 is provided with tension member seats 14 (Fig. 3), in the form of channels having adjacent flanges 15 and which extend 15 outward, downward and forward from the center where there is central a slot extending downward and forward through the bumper head. This slot and the channels are for the reception of the upper bent ends 17 of the 20 tension bars 16, which bars are bent in their own longitudinal plane with a curvature conforming to the bottoms of the channels, 14, and when placed in the channels the correspondings ends 18 of the two tension bars 25 project below the head where they are secured together and to the head by a pin 19 provided with cotter pins as shown. The tension bars extend downward, outward and forward, and are bent in their own plane, at their lower 30 and forward ends, so as to pass completely under each rail in the form of a hook. The pull of these tension members is sustained by tension track fixtures 20 located opposite each other in the track and each of which seats on 35 two adjacent ties adjacent the base of the rail, and on the outside of the rail web, the fixture being spiked to the ties and secured to the web by bolts 6. Its movement endwise of the rails is further obstructed by the shoulder 40 21 which abuts against the front of the adjacent tie. The tension fixture has a body portion beneath the rail and between adjacent ties and which provides a bearing 22 to engage the rail, and beneath the rail and said bearing, a seat 23 for the tension member. There are special advantages in this relative 45 arrangement of said bearing and seat, and it is preferred. By virtue of it tension produced by impact on the bumper head is transmitted to the track fixtures as compression, the part of the track fixtures subjected thereto being adequately supported by the rail on the underside of whose base it bears. Furthermore the track fixture, when located as 50 illustrated and spanning the space between adjacent ties and spiked to each outside the rail, takes up as downward thrust part of the force to be dissipated, the part of each tension fixture extended outward from the rail resisting any tendency to turn the rail up and 55 out about the outer edge of its base, and any tendency to bow or bulge downward the part of the fixture between the seats on the adjacent ties. The seat 23 is formed as a channel 60 extending from the inside of the rail to the

outside of the rail where it terminates in a slot 24 passing up through the fixture. The angle and curvature of the channel are such as to adapt it to receive the adjacent end 25 of the tension bar 16 bent outward and upward into hook form, preferably on a curve of long radius, so that in its passage under the rail it conforms to the seat 23 and passes through the slot 24 as best shown in Fig. 8 and also indicated in Fig. 7. The bearing 75 surface of the seat is square to the tensile forces, that is to say, the tensile forces are parallel to a plane perpendicular to said seat. The end 25 of the tension member is bolted to the fixture and with the fixture to the web of 80 the rail, by bolt 26 which passes therethrough. The full cross section of the tension members is thus maintained throughout except near the extreme ends where the holes for the pin 19 and the bolts 26 are located, so that the 85 parts subjected to maximum strain are not weakened in any way.

The two tension track fixtures are connected and spaced by a pipe 27, each end of which fits over an inwardly projecting cylindrical lug 28 formed on the fixture in rear of the tension bar channels 23. Each of these track fixtures and the adjacent end of the cross bar are thus provided with socket and seat portions permitting the fixtures and cross bar to be assembled by movement toward each other crosswise of the track, and preventing their separation after they are fixed in assembled position. In order to divide the pull of the tension members among 90 various adjacent ties, four as shown here, and as in the case of the compression members, additional anchor bars 11' identical in function with the anchor bars 11 already described but differing therefrom slightly in construction are employed. These bars 11', which seat on the tie under the track fixture have their rear ends formed into hooks or knuckles 12' hooked into a recess 13' in the tension track fixture. The fixture is formed with a bottom recess 29 and the rear end of the anchor bar is confined in this recess when the fixture is spiked to the tie and is thereby prevented from getting loose on the recoil 100 after the bumping post has sustained a shock. A hood 30 covering the extended end of the anchor bar recess and the hook 12' guards against accidental dislodgment of the hook. The tension track fixtures and the connecting cross bar constitute tension track fixture 110 structure seating under the respective rails and to which the tension members are connected adjacent the rails.

It will be observed that the invention avoids the use of rails bent and twisted in different planes as heretofore commonly employed, the re-shaping of such rails to their original form after distortion, as the result of displacement from collision, being beyond the skill of the usual track hand, whereas the simple tension 125

bars bent each only in its own plane can be readily restored to their original shape by the ordinary track gang. It will be noted also that each track fixture is formed of a base portion to engage the ties and an upright wall portion to engage the rail web. By making this wall of about the height indicated, it will serve to form an adequate attachment to various sizes of rails, thus making 10 the bumper structure as a whole adapted to any of the common sizes of railway tracks.

Claims:

1. A bumper post having a bumper head between the track rails, a pair of compression members and a pair of tension members fixed to the bumper head and to the road-bed, track fixtures fastened both to the rails and to the ties and to which the members of one of the pairs are secured, and anchor means 20 connecting said track fixtures to a forward tie or ties.

2. A bumper post having a bumper head between the track rails, a pair of compression members and a pair of tension members fixed to the bumper head and to the road-bed, and two pairs of track fixtures fastened to adjacent ties, the compression members being secured to one pair of track fixtures and the tension members to the other, and anchor bars 30 connecting the respective track fixtures to another tie or ties.

3. In a bumper post, a track fixture secured to the road-bed and having an edge extending transversely of the track, and an anchor bar extending lengthwise of the track also secured to the road-bed and having a hook or knuckle end grasping said edge.

4. In bumper structure, means for reinforcing the bumper element comprising an anchor bar adapted to span the space between and be secured to adjacent ties and having a hook or knuckle end adapted to grasp an edge extending transversely of the track, and spike holes spaced from said hook so as 45 to come opposite the forward tie or ties.

5. In a bumper post, anchoring means for a strain-transmitting member comprising a track fixture fastened to a plurality of adjacent ties and to the rail, and a longitudinal 50 anchor bar having a hook rear end grasping an edge in said track fixture, secured to a tie or ties in advance of the bumper post, and extending therefrom under the corresponding track fixture.

55 6. In bumper structure, means for reinforcing the bumper element comprising a track fixture having in its underside a recess adjoining an edge, and extending longitudinally of the track, a longitudinal anchor bar resting on the tie and occupying said recess and having a hook or knuckle on its end grasping said edge, and means for securing the anchor bar to another tie.

65 7. In bumper structure, means for reinforcing the bumper element comprising a

track fixture having in its underside a recess adjoining an edge and extending longitudinally of the track, and a covering extending over and spaced from said edge, a longitudinal anchor bar resting on the tie, fitting 70 and occupying said recess and having a hook on its end grasping the said edge and occupying the space between the edge and covering, and means for securing the anchor bar to a plurality of ties. 75

8. A bumper post having a bumper head, means for transmitting thrust of impact therefrom to the road bed, tension track fixtures, and means for transmitting tension strain from the bumper head to the road-bed 80 having hooked portions extending down on one side of the rail under the rail and up at the other, said tension track fixtures furnishing seats beneath the rails for the tension transmitting means. 85

9. A bumper post having a bumper head, means for transmitting thrust of impact therefrom to the road-bed, tension track fixtures each having a bearing to engage the rail and a seat beneath the rail bearing, and tension transmitting means secured to the bumper head and having portions extending down and seating on the seats beneath the rail bearings. 90

10. A bumper post having a bumper head, means for transmitting thrust of impact therefrom to the road-bed, and tension members hooked over the bumper head and hooked under the rails so as to extend up and down on both sides of the web of the 100 rail. 95

11. In a bumper post, a bumper head, means for transmitting thrust of impact therefrom to the road-bed, tension track fixtures, the bumper head and tension track fixtures having tension member seats, and tension members having hooked ends of undiminished cross-section seating thereon. 105

12. A bumper post having a bumper head, means for transmitting thrust of impact 110 from said head to the roadbed, track fixtures secured to the rails and to the roadbed at the outside of the respective rails and having seats for tension transmitting means and slots adjacent said seats, and tension transmitting means passing over the bumper head and under the rails from the inside to the outside of the latter and coacting with said seats and extending up through said holes at the outside of the rail webs. 115

13. In a bumper post, a bumper head between the rails, means for transmitting thrust of impact therefrom to the roadbed, a pair of tension track fixtures oppositely located in the track and each having beneath the adjacent rail a seat for a tension member, and a pair of downwardly, forwardly and outwardly extending tension members having corresponding inwardly curved upper ends conforming to bumper head surface and out- 125 130

wardly curved lower ends conforming to said seats, said tension members being in the same plane.

14. In a bumper post, a bumper head having an impact face and tension member channels extending downward, outward and forward from a common slot in the bumper head extending downward in rear of said face.

15. In a bumper post, a bumper head having in rear of its impact face tension member seats over which tension members are adapted to be hooked and between which is a slot down into which their ends extend.

16. In a bumper post, a bumper head having an impact face and at its rear portions extending downward, rearward and outward and adapted to have compression members secured thereto, and having between said portions and its impact face at each side thereof tension bar channels extending downward, outward and forward from a common slot through the bumper head for the receipt of tension members.

17. In a bumper post, a tension member having at one end a hook member adapted to hook over part of a bumper head and at the other a hook member adapted to hook under one of the rails.

18. In a bumper post, a tension bar having its ends bent in opposite directions on curves of long radius to form hooks.

19. In a bumper post, an integral tension member having at opposite sides curved return hook ends for bumper head and road-bed contact respectively.

20. In a bumper post, a tension member having its ends bent in opposite directions to form hook portions at opposite sides of the tension member, the entire tension member including said ends lying in the same plane.

21. In a bumper post, a track fixture for anchoring a tension member adapted to conform substantially to the underside of the rail and to seat on its web at one side of the rail, and having a curved channel extending from one side of the rail base around the part of the track fixture which is adapted to seat on the underside of the rail to the other side of the rail base for the reception of a tension member.

22. In a bumper post, a track fixture for anchoring a tension member adapted to conform substantially to the underside of the rail and to seat on the web of the rail at the outside of the rail, and having a seat extending from the inside of the track base under the part of the track fixture on which the underside of the rail seats to the outside of the rail base, and means to bolt said track fixture and tension member to the rail.

23. In a bumper post, a tension track fixture having a bearing to engage the underside of the base of the rail and seating against the web of the rail and having beneath the rail a seat for a tension member extending down

under the rail from one side of the rail and up through the said fixture at the other side of the rail.

24. In a bumper post, a tension track fixture seating against and secured to the rail web at the outside thereof and seating on and fixed to adjacent ties and having between them a bearing to engage the underside of the base of the rail and a tension bar channel extending under said bearing from the inside 75 of the track to the outside thereof.

25. A bumper post having a pair of tension track fixtures disposed opposite each other in the track, each seating on and fixed to adjacent ties and having between them a 80 bearing to engage the underside of the base of the rail, a tension bar channel extending under said bearing from one side of the rail to the other, and means extending across the track for connecting said fixtures together in 85 rear of said channels.

26. In bumper structure, a pair of track fixtures disposed opposite each other in the track and each having a slot extending crosswise of the track and an undercut recess at the outer end thereof, a cross tie-rod headed at each end having its intermediate portion laterally insertible into said slots when the track fixtures are closely spaced and non-removable therefrom when the fixtures are in assembled 95 position.

27. A bumper post having a bumper head between the rails, a pair of compression members and a pair of tension members fixed to the bumper head and to the road bed, a pair 100 of track fixtures to which the members of one of the pairs are secured located opposite each other in the track and each seated on and secured to adjacent ties and spanning the space between them, and anchor bars connecting 105 said track fixtures to a forward tie or ties.

28. In bumper structure, means for reinforcing the bumper element comprising a track fixture spiked to a tie, and an anchor bar seating on the tie under the track fixture, extending lengthwise of the track spiked to a tie or ties in advance of the track fixture and having a hook or knuckle end grasping a part 110 of said track fixture.

29. A bumper post having a bumper head, means for transmitting thrust of impact therefrom to the road-bed, tension transmitting means secured to the bumper head and to the road-bed in advance of the bumper head, and tension track fixtures each having a bearing to engage the underside of the base of the adjacent rail and receiving the tension transmitting means beneath the rail in substantially the plane of the track.

30. In a bumper post, a compression track 125 fixture adapted to seat on a plurality of ties, secured to the adjacent rail web and having shoulders spaced lengthwise of the track to seat respectively against the front faces of said respective ties.

31. In a bumper post, a compression track fixture adapted to seat on adjacent ties and span the space between them, secured to the adjacent rail web and having a pair of shoulders spaced apart the width of a tie and the space between the adjacent ties to seat against the front faces of said ties. 70
32. A bumper post having a bumper head, means for transmitting thrust of impact therefrom to the road bed, and tension members secured to the bumper head and hooked under and embracing tension track fixture structure below the rail base. 75
33. A bumper post having a bumper head, means for transmitting thrust of impact therefrom to the road bed, tension track fixture structure including tension track fixtures secured to the road bed and a cross bar member connecting them across the track, and means for transmitting tension strain from the bumper head to the road bed having hooked portions extending down adjacent the respective tension track fixtures, embracing the tension track fixture structure and seating on said structure below the plane of the rail base. 80
34. A bumper post having a bumper head, means for transmitting the thrust of impact therefrom to the roadbed, tension connections from the bumper head to the road bed including tension track fixture structure having a cross member in the plane of the track and seating on the under side of the base of the respective rails, and tension members extending downward, outward and forward from the bumper head and embracing said structure below the plane of the rail bases. 85
35. A bumper post having a bumper head, means for transmitting thrust of impact therefrom to the road bed, tension members connecting the bumper head to the road bed, tension track fixtures secured to the ties and to the respective rails and each having a portion bearing on the underside of the base of the rail and interposed between it and the corresponding tension member to act as a seat therefor and to receive as compression the tension to which the tension members are subjected on impact. 90
36. A bumper post having a bumper head, means for transmitting thrust of impact therefrom to the road bed, tension track fixtures disposed opposite each other in the track each having a base seating on and fixed to adjacent ties, spanning the space between them and bearing on and secured to the adjacent rail and having between said ties a bearing to engage the underside of the base of the rail, and beneath it a seat for a tension member, and tension members connecting the bumper head with the road bed respectively extending under the rail and seating on said seat of the adjacent tension track fixture. 105
37. A bumper post having a bumper head, a pair of compression track fixtures each spanning the space between adjacent ties at the inside of the rail and having a base seating on and secured to each of said ties, and having an upright flange member seating against the inside of the rail web and bolted thereto, compression members secured to the bumper head and to the compression track fixtures to transmit the thrust of impact to said fixtures and through them to the rails, ties and road bed, and tension members secured to the bumper head and to the road bed. 110
38. A bumper post having a bumper head, a pair of compression track fixtures each spanning the space between adjacent ties at the inside of the rail and having a base seating on and spiked to each of said ties, and having adjacent the seats of the base on the respective ties, a pair of downwardly extending shoulders spaced apart lengthwise of the track and each abutting on the front face of the adjacent tie, said track fixtures each having a flange member seating against the inside of the rail web and bolted thereto, compression members secured to the bumper head and to the compression track fixtures to transmit the thrust of impact to said fixtures and through them to the rails, ties and road bed, and tension members secured to the bumper head and to the road bed. 115
39. A bumper post having a bumper head, a pair of compression track fixtures located opposite each other in the track, extending lengthwise thereof, seating on and spiked to the ties between the rails and seating on the web of the adjacent rail at the inside of the rail and bolted thereto and having portions extending upward, inward and forward, compression members secured to said portions and to the bumper head to deliver the thrust of impact to the rails, ties and roadbed, tension track fixtures located opposite each other in the track and seating on and spiked to the ties at the outside of the rails, and bearing on and bolted to the web of the adjacent rail, and tension members connecting the bumper head to said tension track fixtures. 120
40. A bumper post having a bumper head, a pair of compression track fixtures located opposite each other in the track and having angularly related flange members seating respectively on the ties at the inside of the rail, and against the web of the rail, compression members secured to the compression fixtures and to the bumper post, tension track fixtures located opposite each other in the track and having angularly related flange members seating respectively on the ties and web of the rail at the outside of the rail, bearing on the underside of the base of the rail, and having seats beneath the respective rails, and tension members extending under the rails and seating on said seats and secured to said tension track fixtures and to the bumper head. 125
41. A bumper post having a bumper head between the track rails, sets of compression 130

track fixtures and of tension track fixtures each seating on adjacent ties, spanning the space between them at one side of the rail and secured to said ties and to the rail webs, compression members and tension members secured to the bumper head and to the corresponding track fixtures and extending respectively downward, outward and rearward, and downward, outward and forward from said bumper head.

42. A bumper post having a bumper head between the track rails, sets of compression track fixtures and of tension track fixtures each seating on adjacent ties, spanning the space between them at one side of the rail and secured to said ties and to the rail webs, a cross bar between adjacent ties located below the rails in substantially the plane of the track and connecting said tension track fixtures, compression members and tension members secured to the bumper head and to the corresponding track fixtures and extending respectively downward, outward and rearward, and downward, outward and forward from said bumper head.

43. A bumper post having a bumper head between the track rails, sets of compression track fixtures and of tension track fixtures each seating on adjacent ties, spanning the space between them at one side of the rail and secured to said ties and to the rail webs, a cross bar between adjacent ties located below the rails in substantially the plane of the track and connecting said tension track fixtures to form tension track fixture structure, said structure seating on the underside of the rail bases, compression members and tension members secured to the bumper head and to the corresponding track fixtures and extending respectively downward, outward and rearward, and downward, outward and forward from said bumper head.

44. A bumper post having a bumper head connected with the road bed by compression members and by tension members, the latter extending downward, forward and outward to a point a little lower than the bases of the adjacent rails and there seating under track fixture structure located in substantially the plane of the track and having bearings engaging the underside of the respective rail bases and including track fixtures secured to the rails and ties.

45. A bumper post according to claim 44 in which the tension members extend under the rails and there seat in tension track fixtures each having a part engaging the underside of the rail and provided beneath the rail with a seat for the tension member.

46. A bumper post according to claim 44 in which the tension members extend under the rails and there seat in tension track fixtures each having a part engaging the underside of the rail and provided beneath the rail with a seat for the tension member and

in which also the track fixture structure includes a connection across the track below the rail bases and in substantially the plane of the track.

47. A bumper post having a bumper head between the track rails, means for transmitting the thrust of the impact therefrom to the road bed, tension track fixtures seating on and secured to the ties and bolted to the rail webs, a cross connection member joining said fixtures in substantially the plane of the track and constituting with them tension track fixture structure seating on the underside of the bases of the respective rails, and tension members extending forward, downward and outward from the bumper head and connected with said tension track fixture structure so as to transmit the tension from the bumper head to said structure, rails and road bed.

48. A bumper post having a bumper head between the rails, means for transmitting thrust of impact therefrom to the roadbed, tension connections from the bumper head to the roadbed including tension track fixture structure comprising tension track fixtures secured to the rails and to the ties and which seat on the underside of the respective rail bases and are connected across the track in substantially the plane of the track, and tension members extending downward, outward and forward from the bumper head and secured to said tension track fixture structure adjacent the rails.

49. A bumper post having a bumper head, means for transmitting the thrust of impact therefrom to the road bed, tension track fixture structure connected across the track seating on the underside of the respective rail bases and including tension track fixtures secured to the road bed adjacent the respective rails, and tension members seating under said tension track fixture structure to transmit tension from the bumper head to said structure, the underside of the rails, and the road bed generally.

50. A bumper post having a bumper head between the track rails, means for transmitting the thrust of the impact therefrom to the road bed, tension track fixtures seating on and secured to the ties and bolted to the rail webs, a cross connection member joining said fixtures in substantially the plane of the track and constituting with them tension track fixture structure seating on the underside of the bases of the respective rails, and tension members connected with the bumper head and with the track fixture structure so as to transmit the tension from the bumper head to said structure, rails and roadbed.

51. A bumper post having a bumper head between the track rails, compression members for transmitting thrust of impact from the bumper head to the track, structure for transmitting tension from the bumper head

- to the track comprising track fixtures seating on, underlying and secured to the respective rails and tension members extending downward, outward and forward from the bumper head and connecting the same to the respective track fixtures, said structure extending under the rail from one side of the rail to the other and embracing the respective adjacent rails at opposite points in the track.
52. A bumper post according to claim 51, having the tension track fixtures connected across the track in substantially the plane of the track.
53. A bumper post having a bumper head between the rails, a pair of compression members and a pair of tension members fixed to the bumper head and to the roadbed, a pair of compression track fixtures secured to the roadbed within and adjacent the rails and to which shock of impact is transmitted by said compression members, a pair of tension track fixtures secured to the roadbed outside of and adjacent the rails, and to which shock of impact is transmitted by said tension members, and anchor bars extending lengthwise of the track and connecting the respective track fixtures with a forward tie or ties, two of said anchor bars being inside and two outside of the rails.
54. In bumper structure, a pair of track fixtures disposed opposite each other in the track and each having a slot extending cross-wise of the track, and an undercut recess adjacent said slot, a rod adapted to be received in said slots and having an enlargement adjacent each end adapted to be located in the corresponding undercut recess by relative movement of said rod and the adjacent fixture cross-wise of the track into assembled position.
55. In bumper structure a pair of tension track fixtures disposed opposite each other in

the track, a cross bar adapted to connect said track fixtures across the track, each of said fixtures and the adjacent end of the cross bar being provided with socket and seat portions permitting the fixtures and cross bar to be assembled by movement toward each other cross wise of the track, and preventing their separation after they are fixed in assembled position.

56. A bumper post having a bumper head, means for transmitting thrust of impact therefrom to the roadbed, and means for transmitting tension strain from the bumper head to the roadbed comprising tension members extending respectively to opposite rails and each having an end curved on a wide radius to form a hook in which the rail is received.

57. A bumper post comprising a bumper head, means for transmitting thrust of impact therefrom to the roadbed as compression, said bumper head having curved seats, longitudinally extending tension members having curved hook portions seating respectively on said seats on the bumper head, and means enabling said tension members to transmit thrust of impact to the roadbed.

58. A bumper post comprising a bumper head, means for transmitting shock of impact therefrom to the roadbed, tension track fixtures secured to the roadbed seating under the base of the adjacent rail, and each having a channel starting at the inside of the rail, where its bottom extends forward from its rear wall and toward the rail, and passing under the rail, and tension members connecting the bumper head with the tension track fixtures and seating in the respective channels.

In testimony whereof, I have signed this specification.

STANLEY W. HAYES.
